Specification for Design.

Patented Oct. 31, 1916.

Application filed August 15, 1916. Serial No. 115,089. Term of patent 14 years.

To all whom it may concern:

Be it known that I, ELNO H. TRUMP, a citizen of the United States, residing at Sebring, in the county of Mahoning and State of Ohio, have invented a new, original, and ornamental Design for a Vehicle-Tire, of which the following is a specification, reference being had to the accompanying drawing, forming part thereof.

In the drawings: Figure 1 is a perspec-

tive view of a vehicle tire embodying my new design. Fig. 2 is a plan view of a portion of the tread of said tire.

I claim:

The ornamental design for a vehicle tire, substantially as shown.
